UNITED STATES PATENT OFFICE.

CHARLTON EUGENE LEAPHART, OF LEXINGTON, SOUTH CAROLINA.

COTTON-PICKER.

993,180.

Specification of Letters Patent. Patented May 23, 1911.

Application filed August 22, 1910. Serial No. 578,364.

To all whom it may concern:

Be it known that I, CHARLTON E. LEAPHART, a citizen of the United States, residing at Lexington, county of Lexington, and 5 State of South Carolina, have invented certain new and useful Improvements in Cotton-Pickers, of which the following is a specification.

My invention relates to cotton pickers, 10 that is to devices for picking the cotton from the bolls and depositing the same in a sack, or receptacle.

The object of my invention is to provide an improved cotton picking device adapted 15 to be carried on the back of a person and which will operate semi-automatically to pick the cotton from the bolls and deposit the same in a detachable receptacle attached to the same.

20 A further object of my invention is to provide a device as mentioned in which the operative parts or gearing shall be protected from the cotton as it passes through the machine, to the end that the cotton fiber shall 25 not be injured and the machine shall not become clogged.

Other objects will appear hereinafter.

With these objects in view my invention 30 consists generally in a casing provided with means for securing the same upon the back of a person, a receptacle detachably secured to the casing, a conduit extending through the casing into said receptacle, a fan for creating a strong current of air through said 35 conduit, means for driving the fan and a flexible suction hose and nozzle extending from the inward end of the conduit.

My invention further consists in a casing 40 provided with means for securing the same to a back of a person, a conduit, fan and suction hose as mentioned, an arm on said casing adapted to extend forwardly beneath one arm of the operator, a hand wheel on the end of said arm in position to be easily operated by the person and means connecting 45 said wheel and fan whereby turning of the former will operate the latter.

My invention further consists in various 50 details of construction and arrangements of parts all as will be fully described hereinafter and particularly pointed out in the claim.

My invention will be more readily understood by reference to the accompanying

drawings forming a part of this specification and in which—

Figure 1 is a perspective view illustrating a cotton picker embodying my invention applied to the back of the operator, Fig. 2 is a side elevation of the device, Fig. 3 is a horizontal section on the line $x-x$ of Fig. 2, Fig. 4 is a vertical section on substantially the line $y-y$ of Fig. 3, and Fig. 5 is a vertical transverse section of a modified form of the device.

Referring now to the drawings 1 indicates the casing which is preferably a hollow rectangular member, and 2, 2, indicate straps for securing the same to the back of the operator by passing under the arms and 70 over the shoulders. Detachably secured to the bottom of the casing 1 is a sack or receptacle 3. This may be secured to the casing in any desired manner but I have illustrated the sack as provided with a reinforcing band 4 having eyes 5 to engage buttons 6 on the lower edge of the casing.

Extending through the casing 1 is a conduit 7. This comprises a fan casing 8 and inlet and outlet portions 9 and 10 respectively which are preferably tangential to the casing 8 and at right angles to each other in order that the inlet portion 9 may extend through the side of the casing and the outlet 10 through the bottom thereof.

11 indicates a rotary fan mounted upon a transverse shaft 12 having bearings in the sides of the casing 8. One end of the shaft 12 is provided with a beveled gear 13 within the casing 1.

Fixed to the side of the casing 1 and extended forwardly therefrom is an arm 14. This is adapted to extend beneath one arm of the operator as shown in Fig. 1, and upon its outer end is mounted a hand wheel 15 provided with a crank handle 16 for turning the same. The wheel 15 preferably comprises a beveled gear as illustrated. Extending longitudinally of the arm 14 is a shaft 17 mounted in bearings 18. The forward end of the shaft 18 is provided with a beveled gear 19 meshing with the gear 15, and the rear end of the shaft is provided with a beveled gear 20.

21 indicates a horizontal shaft mounted 105 in bearings 22 in the casing 1 and having one end extending through the casing and provided with a beveled gear 23 meshing

with the gear 20. The opposite end of the shaft 21 is provided with a beveled gear 24 meshing with the gear 13 on the fan shaft 12.

It is obvious that by turning the hand wheel 15 the fan will be rotated and a strong draft created through the conduit 7 in the direction of the arrows.

Secured to the outer end of the conduit 7 is a flexible suction hose 25 terminating in a flared nozzle 26. In using the device the operator turns the wheel 15 with one hand and grasping the nozzle 26 in the other hand presents the same to the open bolls. The suction created by the fan 11 draws the cotton from the boll and deposits it in the receptacle 3. As soon as the receptacle is full it may be removed and an empty one placed in position.

If desired a motor may be provided for operating the fan and in Fig. 5 I have illustrated the device so equipped. 27 indicates a horizontal partition in the casing 1 upon which is mounted an electric motor 28, a battery 29 and a bracket 30. The bracket 30 has bearings for the motor shaft 31 and a vertical shaft 32 which are provided with intermeshing beveled gears 33 and 34 respectively. The lower end of the shaft 32

is provided with a gear 35 meshing with the gear 13. It is obvious that inasmuch as the device is motor driven, the operator will have both hands free for directing the suction nozzle to the bolls. Therefore in this form two suction hose 25 may be provided.

Having described my invention what I claim as new and desire to secure by Letters Patent is:

A cotton picker comprising a casing and means for securing the same to the back of an operator, in combination with a suction device within said casing, a flexible suction hose extending from said device, an arm on said casing adapted to extend forwardly beneath the arm of the operator, a hand wheel on the end of said forwardly extending arm and means operatively connecting said wheel and said suction device whereby turning of the former will operate the latter, substantially as described.

In testimony whereof I have signed my name to this specification in the presence of two subscribing witnesses.

CHARLTON EUGENE LEAPHART.
